Attorney

UNITED STATES PATENT OFFICE

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN

PAINTING DEVICE

Application filed July 12, 1928. Serial No. 292,107.

This invention relates to painting devices and more particularly to striping instruments.

An object of the invention is to provide an instrument for painting a wavy stripe of uniform width and wavy throughout its length.

Another object of the invention is to provide an instrument for painting a wavy stripe of uniform width and wave concomitantly with the painting of a stripe or stripes arranged adjacent thereto.

A further object of the invention is to provide an instrument for painting a wavy stripe in which a predetermined quantity of paint is metered or fed through a nozzle proportionately to the rate of movement of the instrument over the surface under treatment.

20 A further object of the invention is to provide an instrument for painting a wavy stripe by imparting to a nozzle through which paint is fed an oscillatory movement as the paint is deposited on a surface under treatment, the paint being fed through the nozzle in proportion to the rate of movement of the instrument over the surface.

25 A still further object of the invention is to provide an instrument for painting a wavy stripe wherein paint is metered or fed through a nozzle by a gear pump, and the nozzle caused to oscillate in a horizontal plane by a cam on a rotatable guide so that the rate of movement of the guide determines the rate of movement of the nozzle.

30 A still further object of the invention is to provide an instrument for painting stripes comprising in combination with means for painting parallel stripes, a pump mechanism for metering or feeding paint to an oscillatory nozzle, the operation of the pump and movement of the nozzle being controlled or governed by a rotatable guide member having a plurality of cams thereon arranged within a circle so that upon rotation of the guide member as the instrument is moved over the surface under treatment the pump is operated to feed paint through the nozzle proportionate to the rate of movement of the instrument over the surface un-

der treatment and the nozzle is caused to oscillate in a horizontal plane by the cams carried on the rotatable guide, the nozzle being pressed in engagement with the cams so that the wave will be uniform throughout 55 the length of the stripe.

With these and other objects in view which may be incident to my improvements, the invention consists in the parts and combinations to be hereinafter set forth and 60 claimed, with the understanding that the several necessary elements comprising my invention may be varied in construction, proportion and arrangement, without departing from the spirit or scope of the ap- 65 pended claims.

In order to make my invention more clearly understood I have shown in the accompanying drawings means for carrying the same into practical effect, without limiting the improvements in their useful application to the particular construction, which for the purpose of explanation, has been made the subject of illustration.

Other objects of the invention will appear 75 in the following description taken in connection with the drawings which form a part of this specification, and in which:

Fig. 1 is a top plan view with the containers removed and the distributing shaft 80 in section;

Fig. 2 is a side elevation partly broken away, and partly in dotted lines;

Fig. 3 is an end elevation with the containers broken away, and 85

Fig. 4 is a fragmentary view illustrating the pump mechanism in dotted lines.

Referring to the drawings for more specific details of the invention, 10 represents a body portion which is substantially rectangular in general contour. Positioned on one side of the body portion is a plate 11. This plate has positioned therein a three-gear pump comprising three overlapping transverse bores 12, 13 and 14 in which are 90 arranged three intermeshing gears 15, 16 and 17 and on the opposite side of the body portion is a plate 18 having positioned therein a two-gear pump comprising overlapping transverse bores 19 and 20 in which are 95 100

ranged intermeshing gears 21 and 22, the gear 21 being in axial alignment with the gear 16. The plate 11 is covered by a face plate 23 and the plate 18 is covered by a face plate 24, the plates 11, 18, 23 and 24 being secured to the body portion by means of suitable screws 25 passing transversely through the plates and body portion.

A shaft 26 extends transversely through the body portion and has keyed thereon the gears 16 and 21. This shaft has on one end a roller 28 secured in position by a pin 29 and on the other end a flanged roller 30 keyed on the shaft by a pin 31. The roller 30 is provided with beveled flanges 32, one of which has arranged thereon within a circle, the center of which is in the axis of the roller, a cam 33 having a plurality of lobes, the object of which will hereinafter appear. Supported by the body portion 10 is a shaft 34 having mounted thereon for rotation a roller 35. The shaft 34 is provided with a reduced portion 36 which extends transversely through the body portion and plates and receives a nut 37 by which the shaft is rigidly secured in position.

Positioned intermediate the shaft 26 and the shaft 34 is a distributing shaft 38. This shaft extends normally from the body of the instrument parallel to the shafts 26 and 34 and is provided with circumferential slots 39 and 40 and an axial bore 41. Positioned in the top of the body portion is a container 42 communicating with an intake 43 of the three-gear pump, the corresponding outlet of which is indicated at 44. The outlet 44 communicates with a passage 45 which in turn communicates with the axial bore 41. The container 42 also communicates with an intake 46, the corresponding outlet of which is indicated at 47. The outlet 47 communicates with a passage 48 which in turn communicates with the slot or groove 40 in the circumference of the shaft 38.

Mounted in the top of the body portion is a second container 49 communicating with a passage 50 which leads to the intake 51 of the two-gear pump, the outlet of which is indicated at 52. The outlet 52 communicates with a passage 53 leading to and communicating with the slot 39 in the circumference of the shaft 38.

Positioned on the shaft 38 is a sleeve 54 having formed thereon a nozzle 55 provided with a passage 56 communicating with the groove 40 in the circumference of the shaft 38. The sleeve 54 is provided with a cup 57 in which is positioned a ball 58 having formed thereon a nozzle 59 provided with a passage 60 communicating with a diametrical bore 61 extending through the ball normal to the passage 60. The bore 61 is substantially oval as indicated at 62 so that when fitted on the shaft 38 the nozzle 59 may be oscillated in a horizontal plane and

may be raised or lowered, but is restricted in movement in other directions.

On the outer end of the shaft is a sleeve 63 having formed therein a cup 64 in which is positioned the ball 58 and formed on the sleeve 63 is a nozzle 65 having therein a passage 66 communicating with the axial bore 41 in the shaft 38. On the free end of the shaft 38 is a coil spring 67 secured against displacement by a pin 68, the spring being suitably housed as indicated at 69. The spring 67 retains in position the sleeves 54 and 63 and the ball 58 so that the nozzles carried by these members are maintained in their proper relation to one another, and the nozzles are pressed to engage the surface under treatment by springs 70 secured thereto in any suitable manner and suitably supported in a bracket or pin 71 extending normal from the body portion.

The nozzle 59 is provided with an arm 72 which engages the face of the cam 33 on the guide roller and the arm is held or urged in engagement with the cam by a coil spring 73 positioned between the nozzle 59 and the nozzle 65, the latter nozzle being fixed against lateral movement. By means of this structure the nozzle 59 is caused to oscillate in a horizontal plane at a rate proportionate to the rate of rotation of the guide, and liquid paint is fed through the nozzle at a rate proportionate to the rate of movement of the instrument over the surface under treatment, hence a stripe of uniform width and wave is obtained.

It will be understood that various forms of the invention other than those described above may be used without departing from the spirit or scope of the invention. Accordingly, the invention is to be limited only as indicated by the scope of the appended claims.

Having thus described the various features of my invention, what I claim as new and desire to secure by Letters Patent is:

1. A painting instrument comprising a paint containing chamber, a laterally oscillatory nozzle, means associated therewith for feeding paint from the chamber through the nozzle at a rate proportionate to the rate of movement of the instrument.

2. A mobile painting instrument comprising a chamber, an oscillatory nozzle, means associated therewith for feeding paint from the chamber through the nozzle in a continuous uniform ribbon while the instrument is being moved and means for oscillating the nozzle.

3. A mobile painting instrument comprising a chamber, an oscillatory nozzle, means associated therewith for feeding fluid from the chamber through the nozzle in a continuous stream having a uniform rate of flow and means for oscillating the nozzle.

- a rate proportionate to the rate of travel of the instrument.
4. A painting instrument comprising a chamber, an oscillatory nozzle, means associated therewith for feeding fluid from the chamber through the nozzle at a rate of flow proportionate to the rate of movement of the instrument and means for oscillating the nozzle at a rate proportionate to the rate of movement of the instrument.
5. A mobile painting instrument comprising a chamber, an oscillatory nozzle and means intermediate the chamber and nozzle for feeding fluid through the nozzle in a continuous uniform ribbon during travel of the instrument.
6. A painting instrument comprising a chamber, an oscillatory nozzle, means intermediate the chamber and oscillatory nozzle for feeding fluid from the chamber through the nozzle in proportion to the rate of movement of the instrument and means for oscillating the nozzle in a horizontal plane at a rate proportionate to the rate of movement of the instrument.
7. A painting instrument comprising a chamber, a nozzle, a pump intermediate the chamber and the nozzle, means for operating the pump and means actuated by the pump operating means for oscillating the nozzle.
8. A mobile painting instrument comprising a chamber, a nozzle, a pump mechanism connecting the chamber and the nozzle, means for operating the pump mechanism to feed a continuous ribbon of liquid through the nozzle at a uniform rate of flow while the instrument is traveling and means for oscillating the nozzle in a horizontal plane at a rate proportionate to the rate of movement of the instrument.
9. A painting instrument comprising a chamber, a nozzle, a gear pump connecting the chamber and the nozzle, means for operating the gear pump including a roller guide and means associated with the roller guide for oscillating the nozzle.
10. A mobile painting instrument comprising a chamber, a nozzle, a gear pump connecting the chamber and the nozzle, means for operating the pump to feed fluid from the chamber through the nozzle in a uniform ribbon while the instrument is traveling and means including a cam associated with the pump operating means for oscillating the nozzle in a predetermined path.
11. In a mobile striping instrument, the combination of means for painting parallel stripes, a paint containing chamber, an oscillatory nozzle, means connecting the chamber and the oscillatory nozzle for feeding paint from the chamber through the nozzle in a uniform continuous ribbon during movement of the instrument and means im-
- parting uniform oscillations to the nozzle at a rate proportionate to the rate of travel of the instrument.
12. In a painting instrument, the combination of a chamber, a plurality of nozzles, a pump connecting the container and the nozzles, means for operating the pump and means including a cam for directly oscillating one of the nozzles with uniform oscillations.
13. In a striping instrument, a paint containing chamber, a plurality of nozzles, a pump mechanism connected between the chamber and the nozzles, a second paint containing chamber, a nozzle mounted for oscillation between the first mentioned nozzles, a pump mechanism connected between the second mentioned chamber and the oscillatory nozzle and means for operating the pump mechanisms including a cam for oscillating the oscillatory nozzle with uniform oscillations.
14. In a painting instrument, a paint containing chamber, spaced nozzles, a pump mechanism connecting the chamber and spaced nozzles, a second paint containing chamber, an oscillatory nozzle positioned between the spaced nozzles, a pump mechanism connecting the second mentioned chamber and the oscillatory nozzle, means for operating both pump mechanisms including a guide for the instrument and means carried thereby for oscillating the oscillatory nozzle with uniform oscillations.
15. A mobile painting instrument comprising a paint containing chamber, an oscillatory nozzle, means actuated by the movement of the instrument for feeding paint from the chamber through the nozzle in a liquid stream of uniform quantity, and means for automatically oscillating the nozzle during the travel of the instrument.
16. A mobile painting instrument comprising a paint containing chamber, an oscillatory nozzle, pump mechanism for causing a ribbon of paint to flow from the chamber through the nozzle, a roller for actuating the pump mechanism, said roller being moved across the surface to be painted, and means actuated by the roller for oscillating the nozzle during travel of the instrument.
17. A mobile painting instrument comprising a paint containing chamber, an oscillating nozzle, means including a roller for causing a ribbon of paint to flow from the chamber through the nozzle during travel of the instrument, and a cam on said roller engaging the nozzle to cause oscillation thereof.
18. A mobile painting instrument comprising a paint containing chamber, an oscillatory nozzle having a rigid extension, means including a roller for causing a ribbon of paint to flow from the chamber through the nozzle during travel of the in-

strument, and a cam on the roller engaging the nozzle extension to cause oscillation thereof during rotation of the roller.

19. A painting instrument comprising a plurality of aligned nozzles, one of said nozzles being capable of lateral oscillation relative to the other nozzles, and a source of paint supply, means for causing flow of paint from the source of supply through the nozzles, and means for causing oscillation of the oscillatory nozzle.

20. A painting instrument comprising a plurality of aligned nozzles, one of said nozzles being capable of lateral oscillation relative to the other nozzles, a source of paint supply, means for causing flow of paint from the source of supply through the nozzles, and means including a cam and a spring causing oscillating movement of the oscillatory nozzle.

21. A painting instrument comprising a plurality of nozzles, a shaft on which said nozzles are pivotally mounted, one of said nozzles being oscillatory in a plane parallel with the axis of the shaft, a source of paint supply, means for causing paint to move from the source of supply and through the nozzles in a ribbon, and means causing the nozzle to oscillate in a plane parallel with the shaft axis.

22. A painting instrument comprising a plurality of nozzles, a shaft on which said nozzles are pivotally mounted in adjacent relation, one of said nozzles having a universal joint relation with an adjacent nozzle, a source of paint supply, means for causing paint to move from the source of supply and through the nozzles in a ribbon, and means for causing movement of the nozzle universally mounted in a direction transversely of the pivotal movement of the other nozzles.

23. A painting instrument comprising a plurality of nozzles, a shaft on which said nozzles are pivotally mounted in adjacent parallel relation, two of said nozzles having adjacent recessed faces and another nozzle having a convex end intermediate the concave faces, means for pressing said faces together in tight relation, a source of paint supply, means for causing paint to move from the source of supply through the nozzles in ribbons, and means for causing oscillation of the intermediate nozzle in a direction axially of the shaft.

24. A painting instrument comprising a paint containing chamber, a nozzle communicating with the chamber and mounted to oscillate in two directions, and means associated with the chamber for feeding paint through the nozzle at a rate proportionate to the rate of movement of the instrument.

In testimony whereof I affix my signature.
